UNITED STATES PATENT OFFICE.

ROBERT W. GREENBERG, OF NEW YORK, N. Y.

DENTAL APPARATUS.

1,287,001.

Specification of Letters Patent. Patented Dec. 10, 1918.

Application filed January 22, 1918. Serial No. 213,170.

To all whom it may concern:

Be it known that I, ROBERT W. GREENBERG, a citizen of the United States, residing at New York, in the county and State of New York, have invented new and useful Improvements in Dental Apparatus, of which the following is a specification.

This invention relates to dental instruments or devices particularly adapted for obtaining metal dies of teeth for making gold and like crowns.

Among the objects of my invention is to improve the construction of instruments or devices of the character referred to in the several particulars as will hereinafter more fully appear, and to provide in particular a device of the kind mentioned so constructed and arranged that the model for the metal die is held in the proper place and position in the device before the mold is made. A further object of my invention is to provide a device whereby the mold when completed may be fractured or severed into two substantially equal parts without the necessity of removing the mold from the device for that purpose. Other and further objects of my invention will appear from the following specification.

The invention consists further in the matters hereinafter described and more particularly pointed out in the appended claims.

In the accompanying drawings—

Figure 1 is a top plan view of a device constructed in accordance with my invention;

Fig. 2 is a vertical sectional view, with parts in elevation, taken on line 2—2 of Fig. 1;

Fig. 3 is a transverse sectional view taken on line 3—3 of Fig. 2; and

Fig. 4 is a top plan view of the mold after being fractured or severed into two substantially equal parts by the use of my device.

A dental instrument or apparatus embodying the features of my invention comprises, as illustrated in the drawings, a pair of relatively flat jaws or blades 10 and 11, pivotally connected together at one end so that the same when grasped by the hand of the operator may be drawn one toward the other for severing or splitting a plaster of Paris or like dental mold into substantially two equal half portions or parts. One of said blades or jaws, preferably the one 11, is made substantially L-shaped, with the leg portion thereof extending lengthwise of the

device and foot portion 11* thereof extending across the bottom of the device and being arranged at right-angles thereto, as shown in Fig. 2. The other blade or jaw 10 extends lengthwise of the instrument and is arranged directly opposite the jaw 11 and substantially parallel thereto. The lower end of the jaw or blade 10 is pivotally connected, by a transverse pivot pin 12, with the adjacent or outer end of the cross part or base portion 11* of the other blade 11. In order to prevent the blade 10 from swinging or moving outward or away from the opposite blade 11 a greater distance than required, the former is provided with a lug or stop-member 13, adapted to abut against the cross part or base portion 11* of the blade 11. The inner or opposed edges of the two blades or jaws 10, 11 are beveled off in order to provide the same with sharp or knife like edges 14, 15, which extend lengthwise of the blades, as shown in Figs. 2 and 3.

The free or outer end of each blade 10, 11 is provided with a handle 16, 17, which forms a continuation of the associated blade. Said handles are arranged opposite each other in the same manner as the blades and are secured thereto in any suitable manner, preferably by rivets or like fastening members 18, 18. Extending transversely through the handles 16, 17 are screws 19, 20, there being one in each handle and having screw-threaded or other endwise adjustable connection therewith, so that said screws may be moved or turned endwise toward and from each other. As illustrated, said screws 19, 20 are arranged in alinement, extend at right-angles through the handles, and are threaded through the same just beyond the places of attachment of the handles with the blades 10, 11. By this arrangement the inner ends of the screws 19, 20 are substantially opposite each other. Each screw is provided at its outer end with a thumb piece or enlarged head portion 21, 22, which may be grasped in turning the screws. The inner end of one screw, preferably the one 19, is pointed, while the inner end of the other screw 20 is provided with an arch-shaped bearing block 23, the latter having swiveled or rotatable connection with said screw 20 so that said block may properly engage or bear against the model-carrying member or stem 24, to be presently described. The remaining part of my apparatus or device comprises a flask 25 in the

shape of an open ended tube or sleeve, which may be made of rubber or any other desired material. Said flask 25 has a length substantially equal to the length of the blades 10, 11, as shown in Fig. 2, and, as illustrated, is tubular or cylindric in shape.

The instrument or apparatus described and shown is used in the following manner: The member or stem 24 is made tapered in shape, so as to permit its being readily inserted into the material of which the dental mold is made. At the inner or smaller end of the member 24 is affixed a model 26 of a tooth, the latter being obtained in the usual manner and of the usual form for making a die for a gold or like crown. The flask 25 is then rested on one of its ends on a suitable base or table 27, so as to close the now lower end of said flask. The flask 25 is then filled, to a point short of its now open upper end, with plaster or investment material 28, the latter being in a fluid or like state. Shortly after or before this has been done, the member 24 with its model 26 is inserted between the blades or jaws 10, 11, with the model 26 extending downward toward the cross-piece 11^a of the blade 11, and the member 24 fixed or held in such position between the blades by the screws 19, 20, the latter being turned in the proper directions so as to force their inner ends against the portion of the member 24 interposed therebetween. The member 24 is so positioned and held by the screws that one-half of the same extends on each side of said screws. The blades 10, 11 and the interposed member and model are then oiled or greased so as to prevent such parts from adhering to the molding material 28, whereupon the parts are pressed downward into the molding material in the flask 25 while the molding material is in a soft or fluid condition. The lower end of the model 26 is held sufficiently above the cross or base part of the blade 11 so as to be completely enveloped in the molding material when my apparatus is pressed or forced into the same. The parts are pressed downward into the molding material to the proper extent, preferably until the cross bar comes into contact with the base or table 27, but to limit the distance the blades and model are pressed downward, said blades are provided adjacent the handles with outwardly projecting lugs 29, 29 adapted to contact against the upper edge or rim of the flask 25 and act as stop-members for the parts. The width across the two blades is substantially equal to the inner cross-sectional dimension of the flask 25, so that the blades and member 24 may be readily and easily forced downward into the flask. The latter is preferably made cylindrical, so that no matter at what point the blades are forced into the flask, said blades will be diametrically arranged in the flask and always be in a position to sever or

split the mold formed in the flask into two equal half portions or parts. After the plaster or molding material 28 has set, the entire apparatus is raised from the table and the flask 25 pulled endwise off of the mold 28. 7. One of the screws, preferably the one 19, is then loosened, and the handles grasped by the operator and moved toward each other, as shown in dotted lines in Fig. 2. The inner edges of the blades being sharp or knife-like, the mold 28, in the drawing of the blades together, is fractured or split through the mold cavity formed by the stem 24 and model tooth 26, into almost equal half portions or parts in a plane of the blades, as indicated by the dotted lines 30, 30 in Fig. 3 and as illustrated in full lines in Fig. 4. When this has been accomplished, the blades and model 26 are removed from the fractured mold. Then the two parts 31, 31 of 85 the latter are placed together with the mold cavity 32 therebetween and bound together by wire, or the flask 25 may be used for such purpose. The mold 28 may then be dried and the metal for making the crown be 90 poured into the mold cavity 32, but drying of the mold may be dispensed with in case a metal of a low fusing point is used. The product produced by pouring the metal in the mold cavity 32 is of course the dental 95 crown or part desired.

By the use of my device as described and shown, the making of dental crowns or the like is not only greatly facilitated and rendered more accurate and efficient, but with 100 my device it is possible to produce an accurate mold and sever or split the same efficiently and accurately into two half portions, desired in this character of work. It is to be noted that the blades extend on opposite 105 sides of the mold 28 and also are embedded or project inward into the same and thus sever the mold to that extent before the blades are drawn together. Other and further advantages arising out of the use of 110 my device will be readily apparent to those skilled in the art to which my invention relates.

Although I have shown and described herein in detail one preferred form of device 115 or apparatus embodying the features of my invention, yet it is to be of course understood that the details of construction and arrangement of parts shown may be variously changed and modified without departing 120 from the spirit and scope of my invention, and I do not wish to be limited to the exact details of construction and arrangement of parts illustrated except as pointed out in the appended claims. 125

I claim as my invention:

1. A device of the character described, comprising a pair of pivotally connected blades arranged to receive therebetween a plaster or like dental mold for splitting the 130

- same into two parts upon the drawing of one of said blades toward the other, and said blades being provided with means for holding a dental model therebetween.
- 5 2. A device of the character described, comprising a pair of pivotally connected blades arranged to receive therebetween a plaster or like dental mold for splitting the same into two parts upon the drawing of one of said blades toward the other, and said blades being provided with set-screws for holding a dental model therebetween.
- 10 3. A device of the character described, comprising a pair of blades, one of said blades being provided with a cross-bar, the other of said blades having pivotal connection with said cross-bar so that said blades may be drawn one toward the other, and said blades being provided with means for holding therebetween a dental model.
- 15 4. A device of the character described, comprising a pair of blades, one of said blades being provided with a cross-bar, the other of said blades having pivotal connection with said cross-bar so that said blades may be drawn one toward the other, and said blades being provided with endwise adjustable members for holding a dental model between said blades.
- 20 5. A device of the character described, comprising a pair of blades, one of said blades being provided with a cross-bar, the other of said blades having pivotal connection with said cross-bar so that said blades may be drawn one toward the other, and said blades being provided with endwise adjustable members for holding a dental model between said blades.
- 25 6. A device of the character described, comprising a pair of blades, one of said blades being provided with a cross-bar, the other of said blades having pivotal connection with said cross-bar so that said blades may be drawn one toward the other, and said blades being provided with set-screws for holding a dental model between said blades.
- 30 7. A device of the character described, comprising a pair of blades, one of said blades being provided with a cross-bar, the other of said blades having pivotal connection with said cross-bar so that said blades may be drawn one toward the other, each blade being provided with a handle, and said handles being provided with endwise adjustable members adapted to hold a dental model between said blades.
- 35 8. A device of the character described, comprising a pair of blades, one of said blades being provided with a cross-bar, the other of said blades having pivotal connection with said cross-bar so that said blades may be drawn one toward the other, each blade being provided with a handle, and said handles being provided with set-screws for holding a dental model between said blades.
- 40 9. A device of the character described, comprising two connected blades having portions arranged opposite each other and adapted to receive therebetween a plaster or like dental mold, and said blades being provided with means for holding a dental model therebetween.
- 45 10. A device of the character described, comprising two connected blades having portions arranged opposite each other and adapted to receive therebetween a plaster or like dental mold, and said blades being provided with set screws for holding a dental model therebetween.

In testimony that I claim the foregoing as my invention I affix my signature, in the presence of two witnesses, this 31st day of December, A. D. 1917.

ROBERT W. GREENBERG.
